(57) **CLAIM**

The ornamental design for a bunk bed, as shown and described.

DESCRIPTION

FIG. 1 is a right, front perspective view of a bunk bed showing our new, original and ornamental design.

FIG. 2 is a right side view of the bed shown in FIG. 1.

FIG. 3 is a front view of the bed shown in FIG. 1; and, FIG. 4 is a top view of the bed shown in FIG. 1.

The broken lines are for environmental purposes only and form no part of the claimed design.
